Primary Examiner—T. Chase Nelson(74) *Attorney, Agent, or Firm*—John Yun; Bruce S. Shapiro; Wesley Muller(57) **CLAIM**

The ornamental design for a screwdriver, as shown and described.

DESCRIPTION

FIG. 1 shows a perspective view of a screwdriver of the present invention;

FIG. 2 shows a front view of the screwdriver of the present invention;

FIG. 3 shows a rear view of the screwdriver of the present invention;

FIGS. 4 and 5 show opposite side views of the screwdriver of the present invention;

FIG. 6 shows a top view of the screwdriver of the present invention;

FIG. 7 shows a bottom view of the screwdriver of the present invention; and,

FIG. 8 shows a perspective view of the screwdriver of the present invention in an alternate, extended position.

The broken line depiction of portions of the screwdriver in the FIG. 1, 2, and 8 views is for illustrative purposes only and forms no part of the claimed design.
